CLAIM

The ornamental design for a truck, as shown and described.

DESCRIPTION

FIG. 1 is a front, top, left side perspective view of another aspect of the truck showing our new design;

FIG. 2 is a front, top, right side perspective view of the truck illustrated in FIG. 1;

FIG. 3 is a rear, top, left side perspective view of the truck illustrated in FIG. 1;

FIG. 4 is a rear, top, right side perspective view of the truck illustrated in FIG. 1;

FIG. 5 is a front elevational view of the truck illustrated in FIG. 1;

FIG. 6 is a rear elevational view of the truck illustrated in FIG. 1;

FIG. 7 is a left side elevational view of the truck illustrated in FIG. 1;

FIG. 8 is a right side elevational view of the truck illustrated in FIG. 1; and,

FIG. 9 is a top plan view of the truck illustrated in FIG. 1. The broken lines illustrate portions of the truck that form no part of the claimed design.

1 Claim, 8 Drawing Sheets
